(57) **CLAIM**

The ornamental design for a travel charging valet, as shown and described.

DESCRIPTION

FIG. 1 is a perspective view of a travel charging valet incorporating our new design, wherein the travel charging valet is in a first position;

FIG. 2 is a top plan view of the travel charging valet illustrated in FIG. 1;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a perspective view of the travel charging valet in a second position;

FIG. 9 is a top plan view of the travel charging valet illustrated in FIG. 8;

FIG. 10 is a bottom plan view thereof;

FIG. 11 is a rear elevational view thereof;

FIG. 12 is a front elevational view thereof;

FIG. 13 is a left side elevational view thereof; and,

FIG. 14 is a right side elevational view thereof.

The ornamental design which is claimed is shown in solid lines in the drawings. Any broken lines in the drawings are for illustrative purposes only and form no part of the claimed design.
